FREDERICK R. SCHLICHTING, OF SOUTH ST. PAUL, MINNESOTA

VEHICLE STOPPING DEVICE

Application filed October 16, 1930 Serial No. 489,101.

This invention relates to devices designed for use in roadways for vehicular travel and is herein designated as a vehicle stopping device which indicates its main use. The device is built into roadways flush with the surface thereof, and is preferably installed at various points on all roads leading into a town, or to important road crossings. It embodies a mechanism operated by central control, said control means and the mechanism arranged to operate the stopping device or devices so as to present means projected upwardly from the road surface and transversely of the road, to cause the stopping of vehicles. The mechanism embodies a stop signal and also certain means designed to stop vehicles if the signal is disregarded. The invention is intended mainly for use on highways leading out from important intersections, as in small towns. For example, there may be only one important street intersection in a town, the roads extending therefrom in four directions. With these vehicle stopping devices placed in said roads at predetermined distances a central control station is provided in accessible location. It will now be readily seen that bandit raids and bank robberies can be reduced or eliminated. Bandits hitherto prey largely on small town banks and escape by means of motor cars. When a bank robbery or the like has taken place, alarms of various kinds are used but usually after the robbers have fled in their cars. With a central control my devices, in such instances are put into operation preventing escape of the bandits or at least retarding their flight sufficiently for a posse or other authorities to catch up to them.

In the accompanying drawings Fig. 1 is a perspective view of two roads diverging from a small town, and showing a pair of my devices connected with a central control station.

Fig. 2 is a longitudinal sectional elevation of a roadway, with one of my devices installed in the road and connected to the master control.

Fig. 3 is an enlarged cross-sectional view of one of my road devices revealing its inter-

rior mechanism, the elevation being taken on a vertical plane near one end of the elongated mechanism housing.

Fig. 4 is a longitudinal sectional elevation of one end of my mechanism housing showing the vehicle stopping means in upper operative position and also the stop signal operative in conjunction therewith.

Referring to the drawings by reference numerals and letters, A designates a main highway and B an intersecting or diverging highway extending from a street or road crossing where is located a business building C, as on the main corner of a small town. D represents a master control station near the road crossing or it may be within another building or located in an accessible place near said road intersection.

I will describe the construction of one mechanical road unit, it being understood that they may be used in any suitable number of units.

The road unit comprises an elongated box-like housing 5 of which 5A is the bottom, 5B the long sides and 5C the ends. The box is open upwardly and its length is the same as the width of a road, 6 are a pair of lids lying parallel and longitudinally on the top edges and their adjacent inner edge parts normally close together. 7 are a pair of shafts journaled in the ends 5C, one under each said lid near its inner edge and fixed to said lid, as at 8. These lids, when down provide a smooth surface in a common level with the road surface.

To the lower side of each lid is fixed as at 10 a row of angularly directed prongs 9 pointing downwardly and outwardly from the lower side of each lid. The outer edge of each lid may be beveled as 6B and lies on a corresponding angular face of a side wall 5B. 11 is a number of rigid downwardly directed arms on each lid, arranged in pairs of which both members are directly opposite each other and fixed of course in spaced relation one on each lid. The free ends of said arms are bored for pivotal connection with the upper ends of a pair of links 12, the lower ends of which are bored for pivotal connection, as at 13 to the lower

ends of a pair of actuating links 14 normally in inverted V-shape arrangement, their upper ends bored and in alinement to engage on a long actuating shaft 15 which is parallel to and between the above described arms 11 of the lids. Now it will be understood that a downward pull on shaft 15 will spread the links 12 to the straight line position shown dotted in Fig. 3, links 12 meantime moving upwardly and raising the lids until they are vertical (shown dotted in Fig. 3) and back to back, prongs 9 assuming of course an outward and upward direction both ways from the lids. The beveled edges 6B of the lids are brought together to provide an upwardly directed knife-edge. To assure said upward movement of the lids the lower ends of the actuating links 14 may ride on angular faces 16F of a rigid web 16 fixed in the housing. One of the actuating links 14 as to the left in Fig. 3 may have an outward, offset arm 14A to the outer end of which is pivotally connected a signal actuating link 17, the other end of which is connected at 18 to a signal arm 19 pivoted at 20, one near each end of the box, said arm normally horizontal as shown dotted in Fig. 4 and its free end carrying a sign plate 21 with the word "Stop" on it.

When the main actuator shaft is pulled down to raise the lids, arm 14A and link 17 will raise the signal arm 19 out of the box to vertical position shown in full lines in Fig. 4. With the signals thus swung upwardly traffic must stop or drivers disregarding the stop sign will have their tires ripped open by the prongs 9 and further cut by the knife edge 6B. See tire 22 (Fig. 3).

I have now described preferred mechanical means for raising the lid members and signal to stop traffic. Obviously other mechanical means may be used so I do not wish to limit the means to those shown. All parts must be substantial and of such design as to withstand the weight of any vehicle which may be driven over the device.

23 in Figs. 3 and 2 designate any suitable parts of box 5 projecting therefrom to hold the device rigidly imbedded in concrete or other road material.

A number of mechanical devices may be suitable for causing a downward pull on the main actuator shaft 15. I have shown a lower shaft 24 longitudinally of and within the lower part of the box 5 and journaled in the ends thereof, one end of the shaft extending outwardly of the box and carrying a sheave 25 to which is suitably attached a cable 26. 27 are a number of interior sheaves on shaft 24 to each of which is fixed a cable 28 also connected to shaft 15. The sheaves and cables are so arranged that a pull on cable 26 causes cable 28 to

pull shaft 15 downwardly and open the lids. The pull on cables 26 may be exerted from a central control, as the station marked D in Fig. 1. In said station may be mounted a lever 29 pivoted at 30 to the center of a fixed ratchet gear 31, an arm 29A of lever 29 extending below the fulcrum 30 and having the cable 26 connected to it.

32 is an electric switch in the path of movement of arm 29A to cause closing of the switch and sounding of an alarm 33 in circuit 34. One lever 29 may of course operate a number of the devices or several levers may be provided for selective operation of several devices all remote from said control means. It will now be fully understood that in case of a bank or store robbery the bandits leaving the scene of their work can be stopped by putting a number of these devices in operative positions on all roads leading away from the vicinity of robbery as the devices are preferably some distance away from the central control means.

The advantages of the device have herein been fully set forth and will now be fully understood. For wide roads the device may comprise two or more units in alinement and operable as one unit, the rotary shaft 24 simply being extended through all the units as one shaft.

I claim:

1. A vehicle stopping device of the class described comprising an elongated mechanism housing fixed transversely of and in a roadway, the top of said housing normally fixed in a common plane with the road surface, hinged lids in said housing normally closing its top, a row of prongs fixed to the lower side of each lid member and directed downwardly and outwardly within the housing when said lids are in closed position, means within the housing operatively connected with said lids and remote control means connected to said lid means to raise the latter and position said prongs in upward and outwardly directed position above the surface of the road, said lids being provided one pair to each housing, hinge means at their adjacent edge parts, to provide for raising the lid members to vertical positions, and back to back.

2. The structure specified in claim 1, said lid members comprising each an elongated plate normally closing one half of the housing opening with its free edge arranged to rest on an outer edge of the housing.

3. The structure specified in claim 1, said lid members comprising each an elongated plate normally closing one half of the housing opening with its free edge arranged to rest on an outer edge of the housing, said free edges of the lid members beveled to present an upwardly directed knife edge transversely of and above the road surface for the purpose set forth.

4. A vehicle stopping device comprising
an elongated upwardly opening box ar-
ranged to be fixed transversely of a road
bed, an elongated pair of lids normally
5 closing said open part of the housing and
in a plane common to the road surface, said
lids hingedly mounted edge to edge at the
central part of the housing, a rotatable shaft
10 journaled in the lower part of said housing,
cable actuated means on said shaft for ro-
tating the shaft, and further means within
the housing operatively connected with said
lids and said rotatable shaft to raise the lids
15 simultaneously to upright positions, a row
of prongs fixed on each lid and arranged to
be exposed to contact with the wheels of
vehicles only when said lids are raised.

In testimony whereof I affix my signature.
